REVERSIBLE GARTER

Gustave A. Piepenbring, Stratford, and Werner Beutel, Bridgeport, Conn., assignors to The American Fabrics Company, Bridgeport, Conn., a Corporation of Connecticut

Application January 23, 1931. Serial No. 510,660

5 Claims. (Cl. 241—6)

The present invention relates to garters of the type comprising an adjustable leg encircling band with a hose supporting tab depending therefrom. In the usual garter of this type the article must 5 be made up in right and left form for application on the right and left legs respectively. The use of such garters is bothersome and time consuming, and it is an object of the present invention to provide a garter which is reversible so that it 10 may be worn on either leg and yet have the tab and attachment parts always come at the proper side of the leg.

More specifically, an object of the present invention is to provide a garter with a rotary 15 mounting for the tab so that the garter may be reversed.

A further object of the invention is to provide a novel form of rotary mounting which may be produced at low cost.

20 Other objects and advantages of the invention will appear in the following description of a preferred embodiment and thereafter the novelty and scope of the invention will be pointed out in the claims.

25 In the accompanying drawing;

Figure 1 is a front face view of the garter adapted to be applied to the left leg of the wearer;

Fig. 2 is a view in vertical section taken on 30 the line 2—2 of Fig. 1;

Fig. 3 is a view in transverse section taken on the line 3—3 of Fig. 1;

Fig. 4 is a plan view of a pad blank; and

Fig. 5 is a face view of the garter shown in 35 Fig. 1, but with the leg band inverted so that the garter is adapted for application to the right leg.

In the accompanying drawing, we have used the reference numeral 10 to indicate the leg band of the garter. This band may be of the 40 usual elastic webbing or of leather or other material suitable for the purpose. The leg band is attached at one end to a pad 11 which consists of two plies 12 and 13 respectively.

The pad may be of leather or some other 45 material which will hold its shape and yet is fairly flexible. The construction of the pad is shown clearly in Fig. 4. The plies are of substantially triangular form with the corners of the triangles cut off, and the two plies are integrally connected at one corner. In applying 50 a pad to the band 10, the blank is folded along the line 14.

The free end of the leg band is passed through the usual connecting loop 15 and then is at- 55 tached to usual slide buckle 16 so that the effective

length of the band may be adjusted, as desired. The connecting loop 15 is arranged to be hooked over a stud 17 carried by the body.

As clearly shown in Figs. 2 and 3, the support for the stud 17 consists of a washer 18 which is 60 fitted between the plies 12 and 13. This washer consists of a circular disk provided centrally with an upset cut portion 19 and the latter projects through a hole 20 formed in the outer 65 ply 12. The cup 19 is of a size to fit snugly in the hole 20 so that a bearing is provided to permit of rotation of the washer 18.

The inner end of the stud 17 is of reduced diameter so as to pass through an aperture in a tab connecting member 21 and also an aperture 70 in the cup 19. The stud 17 is then riveted fast to the connecting member and washer so that the stud, connecting member and washer will rotate as a unit in the pad 11. The connecting member 21 is provided with a cross bar 22 about 75 which is looped a tab member 23. This tab is provided with the usual clasp loop 24 and button 25 by which attachment may be made to a hose.

In assembling the garter the washer 18 is first applied to the ply 12 with the cup 19 projecting 80 through the hole 20 and then the tab connecting member 21 and the stud 17 are riveted fast. Thereafter the pad blank is folded on the line 14 and an end of the leg band 10 is inserted between the plies 12 and 13. Then the plies are stitched 85 together along the margins of the pad to fasten the leg band to the pad and also to fasten the plies together with the washer 18 between them.

It will be observed that with this construction 90 the tab member together with the washer 18 may rotate as a unit with respect to the pad. Also, that no metal part of the mounting of the tab on the pad can come into contact with the leg of the wearer. The garter may be applied to 95 either leg by rotating the leg band and pad 11 about the mounting of the tab.

While we have described a specific form of my 100 invention, it will be understood that this is to be taken as illustrative and not limitative and that we are free to make such changes in form, construction and general arrangement of parts as may fall within the spirit and scope of the following claims.

We claim:

1. A garter comprising a leg band, a pad connected thereto, a disk rotatable within the pad, a connecting member exterior to the pad and fixed to the disk, and a hose supporting tab carried by said member, said disk and member being 110

rotatable through at least 180° to reverse the position of the tab with respect to the leg band.

2. A garter comprising a leg band, a double ply pad connected thereto and formed with a hole 5 through one of the plies, a disk fitted between the plies and formed with a cupped portion rotatable in said hole, as a bearing, a connecting member fixed to said cupped portion on the outside of the pad, and a hose supporting tab carried by the 10 connecting member.

3. A garter comprising a double ply pad formed with a hole through one of said plies, a disk fitted between said plies and having a cupped portion rotatable in the hole as a bearing, a connecting member, a hose supporting tab secured thereto, a stud projecting through and riveted to said member and said cupped portion, a leg band having one end thereof connected to the pad, and means at the other end of the band for attachment to said stud.

4. A garter comprising a pad formed of two plies with a hole through one of said plies, a disk fitted between the plies and having a cupped portion rotatable in the hole as a bearing, a connect-

25

ing member, a hose supporting tab secured thereto, a stud projecting through and riveted to said member and said cupped portion, a leg band having one end thereof inserted between the plies, the two plies being stitched together adjacent their margins to secure the leg band thereto and confine the disk therein, and means at the other end of the band for attachment to said stud.

80

5. A garter comprising a pad formed of a single sheet of material and folded to provide two plies, one of the plies having a hole therethrough, a disk fitted between the plies and having a cupped portion rotatable in the hole as a bearing, a connecting member, a hose supporting tab secured thereto, a stud projecting through and riveted to said member and said cupped portion, a leg band having one end thereof inserted between the plies, the two plies being marginally stitched together to secure the leg band thereto and confine the disk therein, and means at the other end of the band for attachment to said stud.
